UNITED STATES PATENT OFFICE

ERWIN C. HORTON, OF HAMBURG, AND HENRY HUEBER, OF BUFFALO, NEW YORK, AS
SIGNORS TO TRICO PRODUCTS CORPORATION, OF BUFFALO, NEW YORK

MULTITONE HORN

Application filed November 28, 1930. Serial No. 498,882.

This invention relates to signal horns for motor vehicles such as automobiles and boats, and more particularly to such signal horns as are adapted to emit a plurality of different pitched signal tones.

The invention contemplates a horn of simple and durable construction and having sound generating elements adapted to be actuated by fluid pressure, which may be the less-than-atmospheric pressure created in the intake manifold of the vehicle engine, or by other means as an electric current. It further comprehends a device, the major parts of which are preferably constructed of light stampings, having a plurality of separate trumpet passages for containing columns of air resonant with the sound generating elements and communicating therewith. It is contemplated that these trumpet passages may be of different lengths whereby the contained air columns will oscillate on different wave lengths and frequencies in order that differently pitched sound notes will be produced. The sound passages are preferably formed of such relative sizes that the sound oscillation therein will be harmonious and present a pleasing, concordant and harmonious sound effect.

The invention further resides in the structural characteristics of the various parts of and of the entire completed horn device which will be described with reference to a typical embodiment of the invention, illustrated in the accompanying drawing, wherein:—

Fig. 1 is a side elevation of the completed horn, a portion thereof being broken away to reveal the features of the interior.

Fig. 2 is a bottom plan sectional view taken about on line 2—2 of Fig. 1.

Fig. 3 is a vertical sectional view looking toward the rear of the horn and taken approximately on line 3—3 of Fig. 1.

Fig. 4 is a fragmentary front elevational view showing the upper and forward portion of the horn; and

Fig. 5 is a detail elevational view, depicting one of the members which cooperates to form the trumpet passages.

As shown in Figs. 1, 2 and 3, the device includes a pair of sound boxes 10, 10, each

containing sound generating mechanism which may be of any suitable type but which is preferably of the character disclosed in our copending application, Serial No. 486,228, filed Oct. 3, 1930, in which the sound impulses are created by the movement of fluid induced by the less-than-atmospheric pressure created by the vehicle engine or by other means. The actuating fluid may be conducted through tubes 11 which may be connected to the intake manifold of the engine.

Tubular extensions 12, 12 are formed on the sound boxes 10 for telescopically receiving tubular extensions 13, 14 formed with the trumpet members which compose the body 14 of the device. As shown in Figs. 2 and 3, the body comprises a pair of opposed plates 15 and 16, each having a serpentine or substantially S-shaped depression 17 formed thereon. The depressions, which are preferably semi-circular in cross section, of the plates 15 and 16 terminate respectively in the outwardly extending portions 13 and 14, and increase in depth or radius from the tubular ports 13, 14 to the opposite ends 18, 19 thereof, the latter portions of which may each be formed with a shouldered recess 21 for a purpose to be hereinafter described.

A flat partition member 22, shown in Fig. 1 and of outline similar to that of the plates 15 and 16, is disposed between the latter, and forms with the depressed portions 17 a pair of opposed sound or trumpet passages 23 and 24. The latter are, in the illustrated embodiment, of substantially S-shape and of increasing semi-circular cross-section from the initial ends 13, 14 to the portions 18, 19 thereof. A bell 25 may be pressed into the seat formed by the shouldered portions 21. A partition member 26, shown in Fig. 1 and seated in the bell, provides an extension of the partition plate 22 and with the bell defines the final end portions of the passage.

A screen 27, for excluding insects, dirt and other extraneous matter from the interior of the body 14 and the sound boxes 10, may be secured to the bell near the mouth thereof. Any desired manner of securing the screen in place may be utilized, but it is preferred to accomplish this by pressing the screen into

an annular depression 28 formed about the bell.

As may be readily observed from Figs. 1 and 2, the passage 23 is, in this embodiment of the invention, shorter than the passage 24, the sound box 10, communicating with the latter, being disposed rearwardly of the other sound box, and the rearward connecting tubular portion 14. Portions 29 of the plate members 15 and 16 adjacent the depressions 17 and the tubular extensions 13 and 14 abut the partition 22 and may be secured thereto by welding or by other methods.

Sound producing oscillations set up in the sound boxes 10 will be modified and augmented in the trumpet passages 23 and 24, the latter preferably being of such lengths that the air columns therein will be in resonance with the sound generating means and the oscillations of one air column will be in harmony with the oscillations of the other. The sound boxes may be actuated independently of each other to produce different sound notes for different traffic conditions or may be simultaneously actuated to produce a concordant note.

It will be understood that the parts comprising the horn body may be economically manufactured by stamping them from sheet metal or like material, and that such parts may be readily assembled by welding, riveting, or the like. The tone qualities of the horn may be made as desired, the arrangement described making the device susceptible of changes in size and proportion to secure various sound effects, without departing from the general design.

It will be further understood that the specific device described may be modified as to various structural details, and it is intended that the invention should be commensurate with the scope of the appended claims.

What is claimed is:

1. A horn comprising a plurality of sound boxes, a body member comprising a pair of plates each having complementary depressions, said depressions together composing a trumpet passage, a partition member for dividing said trumpet passage, and said horn having passages connecting said sound boxes with said passage divisions.

2. A horn comprising a pair of sound boxes, a trumpet member having a tubular portion for engaging each of said sound boxes, said trumpet member comprising a pair of sections each having a continuous deformation therein, said deformations together defining a chamber extending from said tubular portions to an edge of said sections, and a partition in said chamber dividing the same into a pair of trumpet passages, each of said passages communicating with one of said tubular portions.

3. A trumpet for horns comprising a plurality of plates each having a continuous

deformation therein, partition means secured between said plates, said partition means cooperating with said deformations to define a plurality of trumpet passages, a bell secured to said plates, and said trumpet passages merging into said bell.

4. A trumpet for horns comprising a pair of plates each having a continuous deformation therein, a partition member between said plates and abutting the surfaces thereof adjacent said deformations, said partition member coacting with said deformation to define a pair of trumpet passages.

5. A trumpet for horns comprising a pair of plates secured to opposite sides of a partition member, said plates and partition member being of substantially the same contour, a serpentine deformation in each of said plates cooperating with said partition member to define a pair of serpentine trumpet passages, each of said passages increasing in cross-sectional area from one end thereof to the opposite end thereof.

6. A trumpet for horns comprising a pair of substantially complementary plates each having a serpentine deformation thereon, said deformations complementing each other to form a serpentine passage, a partition member disposed between and in contact with each of said pair of plates, said member dividing said passage into a pair of sound passages.

7. A trumpet for horns comprising a pair of substantially complementary plates each having a serpentine deformation thereon, a partition member disposed between said plates and cooperating with said deformations to define a pair of trumpet passages, said passages being of different lengths.

8. A trumpet for horns comprising a pair of complementary flat plates of substantially rectangular design, said plates having channels formed therein, a partition between said plates, said partition cooperating with the channeled portions of the plates to form a pair of sound passages opening at one end at marginal portions of the plates, openings formed in said plates at the other ends of said channels, the length of each of said sound passages being greater than either dimension of the plates.

9. In a horn a trumpet member comprising a pair of sections each having a continuous deformation therein, a partition member between said plates and cooperating with said deformations to form a pair of sound passages, said passages being of different lengths and each opening at one end through a marginal portion of said plates, openings in said plates forming the opposite terminals of said passages, and a sound box secured adjacent each of said openings, whereby a multi-tone sound note may be produced by the horn.

10. A trumpet for horns comprising a pair of complementary sections each having a con-

tinuous deformation therein, said deformations extending to the marginal portions of the sections, shouldered recesses at said marginal portions, a bell seated in said recesses, 5 and partition means in said bell and between said sections for cooperating with said bell and plates to form a pair of sound passages.

11. A trumpet for horns comprising a body portion having a pair of trumpet passages 10 formed side by side therein, a bell on said body portion at the opening of said passages, partition means dividing the interior of said bell into a pair of spaces each communicating with one of said trumpet passages, an 15 annular recess about said bell, and a screen seated in said recess.

12. A multi-horn for motor vehicles and the like comprising a unitary trumpet structure having a plurality of sound passages 20 therein differing as to lengths, and a sound generating box for each sound passage independently operable from the companion sound generating box.

13. A multi-tone horn for vehicles and the 25 like, comprising an elongated trumpet member of increasing diameter from one end to the other end, the larger end being open, a sound generating unit connected to the smaller end of the member, and another sound 30 generating unit connected to a medial portion of the trumpet member.
